UNITED STATES PATENT OFFICE.

JOHN W. HAYWARD, OF ST. JOHN'S, NEWFOUNDLAND.

BOTTLE-CORK ATTACHMENT.

SPECIFICATION forming part of Letters Patent No. 328,672, dated October 20, 1885.

Application filed May 7, 1885. Serial No. 164,639. (No model.)

To all whom it may concern:

Be it known that I, JOHN W. HAYWARD, of St. John's, Newfoundland, have invented a new and Improved Bottle-Cork Attachment, 5 of which the following is a full, clear, and exact description.

The object of my invention is to provide a new and improved attachment for bottle-corks, whereby the same can very readily be removed 10 without using a corkscrew or destroying or mutilating the cork, and which attachment serves also as a seal and to tie the cork in the bottle.

The invention consists in the combination, 15 with a cork having slits on its sides, of a cord or band in the said slits and passed over the inner end of the cork.

Reference is to be had to the accompanying drawings, forming part of this specification, 20 in which similar letters of reference indicate corresponding parts in all the figures.

Figures 1, 2, and 3 show modifications of 25 bottle-corks provided with my improved attachment. Fig. 4 shows the manner of tying the cork on the bottle-head by means of the attachment. Fig. 5 shows a perspective of the upper end of a bottle and cork, showing the manner of fastening the cork on wire loops. Fig. 6 is a plan view of the same. Fig. 7 is a 30 side view of a bottle-neck having a cap. Fig. 8 is a perspective view of the protecting-cap.

The cork A is provided with slits B opposite each other in the sides and extending from end to end. A band, C, is passed into the 35 said slits, passes over the lower end of the cork, and forms a loop, D, on the upper end of the cork, by means of which loop the cork can be withdrawn from the bottle-neck very easily and rapidly.

In place of the band C, a cord, E, may be 40 used. In this case a button, F, of horn, bone, or other suitable material, is placed against the bottom of the cork, to prevent the cord cutting into the cork.

The ends of the cord can be tied together 45 and a seal or tag, G, secured to one end of the cord, as shown in Fig. 2.

To tie the cork on the bottle, the cords E are passed around the neck H of the bottle below 50 the head J, and are then tied above the cork, as shown in Fig. 4.

For bottles containing liquids under considerable pressure the cords E are held by wire loops K, projecting upward from a wire, L, surrounding the neck directly below the head J, the cords being passed through the loops K, as shown in Fig. 5, and then tied, as shown in Fig. 6. A cap, M, of tin-foil is drawn over the head and neck of the bottle, and holds the end of the cord E and the tag G against the bottle.

By pulling upward the tag G the cord E rips the cap J. To prevent the cords leaving the slits B, an S-shaped wire, T, is placed upon the top of the cork, the end hooks surrounding the cord, as shown; or a round wad or cap, W, of rubber or other flexible material, provided with a slit, W', is used, through which slit the cords can be passed, whereby they may be held together and are not cut.

To extract the cork it is only necessary to pull on the loop D or cords E, and no corkscrew or other implement is required.

The cork can be used repeatedly, as it is not mutilated by being withdrawn.

The cork can be secured and tied in the bottle-head very securely and rapidly.

The cork is compressed while being drawn, and not expanded, as it is by the corkscrew, and thus the friction is reduced and binding of the cork prevented to a great extent.

In place of the cords E, wires or chains may be used.

Having thus described my invention, what I claim as new, and desire to secure by Letters Patent, is—

1. The combination, with a cork having slits in its sides, of a cord, band, or wire passed through the slits, and of a slotted plate or wire on the top of the cork for holding the cords, substantially as herein shown and described.

2. The combination, with a bottle, of the wire L and loops K, the cork A, and the cord E on the same, substantially as herein shown and described.

JOHN W. HAYWARD.
